CIRCUS PULL TOY

John Dasenbrock, Poughkeepsie, N. Y.

Application August 22, 1957, Serial No. 47,479

Term of patent 7 years

(Cl. D34—15)

FIG. 1

FIG. 2

FIG. 3

FIG. 4

FIG. 5

Figure 1 is a side elevational view of a circus pull toy embodying my new design;

Figure 2 is a side elevational view thereof showing the side opposite that in Fig. 1;

Figure 3 is a front elevational view thereof;

Figure 4 is a rear elevational view thereof; and

Figure 5 is a perspective view thereof.

I claim:

The ornamental design for a circus pull toy, as shown.
